UNITED STATES PATENT OFFICE.

WILLIAM F. ALBERT, OF DETROIT, MICHIGAN, ASSIGNOR TO AMERICAN LADY CORSET COMPANY, OF DETROIT, MICHIGAN, A CORPORATION OF MICHIGAN.

CORSET.

Application filed March 24, 1919. Serial No. 284,811.

To all whom it may concern:

Be it known that I, WILLIAM F. ALBERT, a citizen of the United States of America, residing at Detroit, in the county of Wayne 5 and State of Michigan, have invented certain new and useful Improvements in Corsets, of which the following is a specification, reference being had therein to the accompanying drawing.

10 This invention relates to corsets and more particularly to corsets of the front lacing type. It is the object of the invention to provide a corset having its front portion sufficiently extended downwardly to form 15 an abdominal covering and support, and to present a smooth surface to be embraced by exterior garments, so that the latter may fit snugly, presenting an improved appearance and securing increased comfort as compared to corsets having the ordinary cut-away front portion.

20 A further object is to provide a corset having an abdominal portion, as above set forth, which portion is provided with an 25 individual lacing permitting it to be conformed to the body as snugly as may be desired, said lacing having a sufficient elasticity to permit a certain amount of expansion or contraction in the lower portion 30 of the garment such as has hitherto been secured only by providing the body of the garment with elastic portions.

In the accompanying drawings:

35 Figure 1 is a front view of one form of the invention; and

Figure 2 is a similar view of an alternative form.

40 In these views, the reference character A designates an ordinary lacing arranged at the front of a corset body B and extending between a row of eyelets C adjacent one edge of said body, and a corresponding row 45 of eyelets D provided in a vertically-elongated strip E connected by quick detachable fastenings F to the other vertical edge of the body B. The strip E extends from the top of the corset to substantially the 50 waist line thereof. On the lower or abdominal portion of the garment, the edge thereof with which said strip has quick detachable connection carries the flap G forming a flexible continuation of said strip having a width substantially equal to that of the strip. The adjacent ends of said flap 55 and strip slightly overlap and are adapted

to be connected by quick detachable fasteners H and I. Said flap is provided with a row of eyelets J in alignment with the eyelets of the strip E and through the eyelets J and the lowermost eyelets C of the 60 opposed edge portion of the body B there is extended a lacing K formed of material having sufficient elasticity to permit a certain amount of expansion and contraction in the abdominal portion of the garment 65 when the same is in use. At the lower edge of the flap G and at a corresponding point upon the opposite edge portion of the body B, there are secured hose supporters L which, when the garment is in use, exert 70 a tension upon the engaged portions of the garment, whereby said portions are prevented from wrinkling and are held snugly in abdominal engagement with the body.

75 The form of the invention shown in Figure 1 is best adapted for use by persons who are somewhat stout, since in a garment designed for such persons, there is a greater necessity for expansion and contraction in the abdominal portion of the garment and the elastic lacing allows the necessary yielding and may be adjusted whenever desired to secure a tension satisfactory to the wearer. The construction shown in Figure 2 is 80 adapted for persons of a comparatively slender build, the elastic lacing in such cases being unnecessary and being omitted as are also the eyelets in the flap G and in the lower portion of the opposed edge of the body B.

85 In both forms of the invention there is secured an abdominal supporting effect and the front abdominal portion of the body is provided with a smooth unwrinkled covering which permits the exterior garments to fit snugly and comfortably. The tension applied vertically to the flap G by the hose supporter L is transmitted to the strip E by the fasteners H and I and the wrinkling and gapping which would occur in the absence 90 of said fasteners, is avoided.

95 In various corset constructions hitherto designed, elastic inserts have been sewed in the lower portion of the garment to permit of such expansion and contraction as is at various times desirable as, for example, when the wearer of the garment changes 100 from a standing to a sitting position, or vice versa. Such constructions have been found objectionable, however, because of the fact that the elasticity of the inserts becomes ex- 110

hausted a considerable time before the garment is worn out and any provision for giving renewed elasticity to the garment is lacking. In applicant's construction, above described, this defect is remedied since the lacing K is depended upon to provide the requisite elasticity and when said lacing loses this quality, it can readily be renewed at a very slight expense.

10 What I claim as my invention is:

1. A corset comprising a body member, a vertically elongated strip detachably secured to a vertical edge of said body member, a lacing connecting said strip to the opposed vertical edge of the body member, a flap arranged beneath said strip forming a downward extension thereof and permanently secured directly to the first mentioned vertical edge, and hose supporters respectively engaged with said flap and with the opposed edge of the body member.

2. A corset comprising a body member, a strip detachably secured to a vertical edge of said body member, a lacing securing said

strip to the opposed vertical edge of the 25 body member, a flap carried by the edge of the body member with which said strip is engaged, said flap being arranged beneath said strip and forming a downward extension thereof, and a facing connecting said 30 flap with the opposed edge of the body member.

3. A corset comprising a body member having adjacent vertical edges at the front thereof, a strip detachably secured to one of 35 said edges, a facing connecting said strip to the other of said edges, a flap projecting from the edge to which said strip is detachably secured, said flap forming an extension 40 of said strip beneath the same, means detachably engaging the upper edge of said flap with the lower edge of said strip, and hose supporting members attached to said flap and to the corresponding opposed edge 45 portion of the body member.

In testimony whereof I affix my signature.

WILLIAM F. ALBERT.
